UNITED STATES PATENT OFFICE.

JAMES SPRUCE, OF WATERBURY, CONNECTICUT, ASSIGNOR TO THE
SCOVILL MANUFACTURING COMPANY, OF SAME PLACE.

IMPROVEMENT IN BUCKLES.

Specification forming part of Letters Patent No. **150,369**, dated April 28, 1874; application filed
March 26, 1874.

To all whom it may concern:

Be it known that I, JAMES SPRUCE, of Waterbury, in the county of New Haven and State of Connecticut, have invented a new Improvement in Buckles; and I do hereby declare the following, when taken in connection with the accompanying drawings and the letters of reference marked thereon, to be a full, clear, and exact description of the same, and which said drawings constitute part of this specification, and represent, in—

Figure 1, a view of the buckle complete; Figs. 2, 3, and 4, the parts detached; Fig. 5, the frame, loop, and tongues, as in their relative positions when the buckle is complete; and in Fig. 6, a section on line *xx*.

This invention relates to an improvement in the construction of that class of buckles designed especially for fastening or adjusting wearing apparel, and particularly those which are provided with a loop by which to attach the fixed end of the strap or band; and the invention consists in forming the frame in one piece with one side open, the loop and tongues in a second piece, the tongues at the base distant from each other corresponding to the opening in the side of the frame, and so as to lie therein, combined with a sleeve, which, closed around the open side of the frame and tongue side of the loop, secures the two parts together, and so that the tongues and loop may be turned to open or close the buckle.

A is the frame, preferably formed from wire, bent into the desired form, and so as to leave an open space, *a*, upon one side; B, the loop,

is also made from wire bent into form, as seen in Fig. 3, the two ends turned substantially parallel to each other to form the tongues *b b*, these tongues distant from each other corresponding to the opening *a* in the frame. These parts are set together as seen in Fig. 5, the side of the loop outside the tongues lying close to the ends of the open side of the frame, the tongues in the opening *a*. In this position they are secured by a sleeve, *d*. This sleeve is preferably formed from thin sheet metal, and perforated, as at *i i*, corresponding to the tongues, so as to pass over the tongues and extend to the right and left therefrom. This is closed around the side of the frame and loop, as seen in Fig. 6, firmly securing and hinging them together, so that the tongues may be freely moved to or from the opposite side of the frame.

While I prefer to make the sleeve as described, it may be made in two parts, one upon one end of the frame, and the other upon the other end, and inclose corresponding portions of the loop.

*I claim as my invention—

The herein-described buckle consisting of the open-sided frame A, the tongues *b b*, and loop B in one piece, and the inclosing sleeve or band *d*, by which the parts are secured and hinged together, substantially as specified.

JAMES SPRUCE.
